UNITED STATES PATENT OFFICE.

ALBERT ROSA, OF MILWAUKEE, WISCONSIN, ASSIGNOR TO JENNIE A. ZINN,
OF SAME PLACE.

SAD-IRON.

SPECIFICATION forming part of Letters Patent No. 400,796, dated April 2, 1889.

Application filed February 14, 1887. Serial No. 227,533. (No model.)

To all whom it may concern:

Be it known that I, ALBERT ROSA, of Milwaukee, in the county of Milwaukee, and in the State of Wisconsin, have invented certain new and useful Improvements in Sad-Irons; and I do hereby declare that the following is a full, clear, and exact description thereof.

My invention relates to that class of sad-irons that are made hollow and heated by burning charcoal placed therein, said invention consisting in certain peculiarities of construction and combination of parts, to be hereinafter described with reference to the accompanying drawings and subsequently claimed.

Figure 1 represents a perspective view of a sad-iron constructed according to my invention, and Fig. 2 a vertical transverse section of a portion of the iron.

Referring by letter to the drawings, A represents the hollow shell or body-piece of my iron, provided with a smoothing-face, B, and hinged cover C, the latter having a handle, D, and a pivoted latch-piece, E, that engages 25 a lug, F, projecting up from said shell. The hinged cover C, as illustrated in Fig. 1, has its edges provided with a series of depending lugs arranged at suitable intervals and designed to rest upon the adjacent edges of the 30 shell A, whereby a draft-space is left between the upper edges of said shell and the under side of the cover when the latter is in its normal position, the apertures between the lugs serving as draft-openings and the lugs 35 as guards to prevent the escape of sparks from burning charcoal.

The sides of the shell A are provided with longitudinal draft-openings G and bearings H H' for the journals I' of plates or dampers 40 I for said openings. Each of the plates or dampers I has a handle, J, and operative in the bearings H are set-screws K, to hold said plates in any position to which they may be

adjusted. The rear end of the iron is provided with a draft-opening, L, and has pivoted thereto a guide-plate, M, provided with slots or perforations a.

Operative in the guide-plate M is a slide, N, having slots or perforations b, arranged to be brought in and out of register with the 45 ones a in said guide-plate, this construction being similar to that described in my application for patent filed February 7, 1887, Serial No. 226,784.

By means of the adjustable plates or dampers I the area of the openings G in the sides of the iron may be varied to regulate the draft for the purpose of increasing or diminishing the heat, and it will be noticed that said plates are arranged to deflect the air and 50 cause it to strike the mass of fuel at the lowest possible point. When the iron is temporarily laid aside, all the lower draft-openings may be closed in order to effect a saving in fuel.

Having thus fully described my invention, what I claim as new, and desire to secure by Letters Patent, is—

A hollow sad-iron having its body portion provided with a cover of such construction 70 that a draft-space and openings are left between said shell and cover when the latter is in its normal position, longitudinal openings in the sides of the shell near its base, plates or dampers journaled in bearings on said 75 shell, and set-screws arranged to impinge against the journals of said plates or dampers, substantially as described.

In testimony that I claim the foregoing I have hereunto set my hand, at Milwaukee, in 80 the county of Milwaukee and State of Wisconsin, in the presence of two witnesses.

ALBERT ROSA.

Witnesses:

H. G. UNDERWOOD,
N. E. OLIPHANT.

400796

It is hereby certified that the name of the assignee in Letters Patent No. 400,796, granted April 2, 1889, upon the application of Albert Rosa, of Milwaukee, Wisconsin, for an improvement in "Sad Irons," was erroneously written and printed "Jennie A. Zinn," whereas said name should have been written and printed *Jennie A. Zinns*; and that the said Letters Patent should be read with this correction therein that the same may conform to the corrected files and records of the case in the Patent Office.

Signed, countersigned, and sealed this 23d day of April, A. D. 1889.

[SEAL.]

CYRUS BUSSEY,

Assistant Secretary of the Interior.

Countersigned:

C. E. MITCHELL,

Commissioner of Patents.
